UNITED STATES PATENT OFFICE.

WILLIAM W. RANDALL, OF MARSHFIELD, ASSIGNOR OF ONE-HALF TO
HOWARD C. BARNES, OF BOSTON, MASSACHUSETTS.

BOX-FASTENER.

SPECIFICATION forming part of Letters Patent No. 275,853, dated April 17, 1883.

Application filed January 29, 1883. (No model.)

To all whom it may concern:

Be it known that I, WILLIAM W. RANDALL, a citizen of the United States, residing at Marshfield, in the county of Plymouth and State of Massachusetts, have invented a new and useful Spring-Catch for Boxes, of which the following is a specification.

My invention relates to that class of catches which are self-locking, the object being to construct a catch that shall be strong and yet resilient, the movement of the spring being limited in both directions, so that no injurious overstrain can be brought to bear upon it. I attain this object by the mechanism illustrated in the accompanying drawings, in which—

Figure 1 shows a violin-case in perspective with my improved catches applied. Fig. 2 is a section through a part of the case and catch, the case being closed. Fig. 3 is a section of the same, the case being partly open. Figs. 4 and 5 show details.

In the drawings, A and B represent the lid and body of the case or box. To the body part B (see Figs. 2 and 3) I rigidly attach a piece, M, having a notch at its upper end, as shown. This part has no movement, its function being a passive one. To the lid of the box I attach a plate-spring, D, curved, as shown in Figs. 2, 3, and 5, and provided with an opening at H, the function of said opening H being to lock into the notch in the piece M, the connection being shown in Fig. 2, which illustrates the device in its locked position. To

unlock the catch the user has simply to draw the finger-piece D' of the plate-spring D outwardly, so that it may clear the notch in the piece M.

In constructing my device I prefer the use of a plate, C, provided with openings at L and K, the opening L being adapted to receive the lower end of the spring-plate D, as shown in Figs. 2 and 3, the opening K admitting the upper end of the notched piece M to engage with the spring-plate D.

It may be seen that the motion of the spring-plate D is limited in both directions—that is, if it is pulled outwardly the plate C will arrest its motion. If it is pushed inwardly, then the portion D' will come in contact with the lower face of the case B, and thus be limited in that direction.

In some applications it may be desirable to attach the spring-plate D to the inner side of the lid A, in which case the spring-plate D will still retain its essential features and shape, although the offset at D', Fig. 3, will be greater.

I claim as my invention—

The combination of the spring-plate D, provided with an opening, H, offset D', finger-piece D', and plate C with the notched piece M, all operating together substantially as described, and for the purpose set forth.

WILLIAM W. RANDALL.
